UNITED STATES PATENT OFFICE.

ALBERT W. FULLER, OF LAUREL, MONTANA.

DITCH-CUTTING MACHINE.

Application filed August 24, 1921. Serial No. 495,037. Renewed August 29, 1923.

To all whom it may concern:

Be it known that I, ALBERT W. FULLER, a citizen of the United States, residing at Laurel, in the county of Yellowstone and State of Montana, have invented certain new and useful Improvements in Ditch-Cutting Machines, of which the following is a specification, reference being had to the accompanying drawings.

10 This invention relates to ditch cutting or digging machines, and particularly to machines designed for cutting relatively shallow irrigation ditches.

15 The general object of my invention is to provide a machine of this character which is very simple and which is thoroughly effective for the purpose of planing and grading new irrigation ditches, but which may be also used for cleaning old ditches 20 and cutting old ditch banks with a great saving both in time and labor.

25 A further object is to provide a mechanism of this character which is adapted to form a complete ditch with one cut of the machine and which may be used either with horses or a tractor.

30 And a further object is to provide a machine of this character so constructed that the depth of the ditch may be regulated.

35 Other objects will appear in the course of the following description.

My invention is illustrated in the accompanying drawings, wherein:

Figure 1 is a top plan view of the ditch digging machine constructed in accordance 35 with my invention;

Figure 2 is a side elevation thereof, showing the supporting wheels raised;

Figure 3 is an under side plan view;

Figure 4 is a section on the line 4—4 of

Figure 1.

40 Referring to these figures, it will be seen that my machine comprises a triangular body designated generally 10. This body is formed of relatively heavy sheet metal and is formed to provide a flat upper surface 11 and downwardly extending flanges or sides 12, these sides being preferably about a foot in depth. Braces 14 are disposed between 45 these sides to hold them apart and against any strain, the braces having T-heads insertible into guides 13.

45 Mounted in bearings upon the upper face of the body adjacent the rear end thereof is a transverse axle 15 which is cranked at its ends, as at 16, and carries a wheel 17. This

axle is rotatably mounted in the bearings 18, and for the purpose of oscillating this axle I provide the lever or handle 19 which is attached to the axle and which operates 60 over an arcuate toothed rack 20. The handle 19 is provided with the usual locking bolt 21 operatively connected to a hand grip 22 whereby the locking bolt may be retracted from the teeth of the arcuate rack to permit 65 the handle to be oscillated and thus the axle to be oscillated. Forward of the middle of the machine there is provided the front axle 23 which is also cranked at its ends and carries the front wheels 24. This is also 70 mounted in suitable bearings on the upper face of the body and has a handle 25 operating over an arcuate rack 26, the handle being provided with the same locking means as is disposed on the rear handle. The for- 75

ward end of the body is pivotally connected to a tongue or draw bar 27 whereby draft may be applied to the machine to draw it forward. It will be obvious that by oscillating the axles 15 and 23, the body may be 80 elevated as a whole or depressed as a whole, or that the forward or rear ends of the body may be elevated or depressed independently of the other end. The wheels 24 and 17 are designed to run along the ground on each 85 side of the proposed ditch while the machine cuts the ditch, and the wheels may be adjusted to cut any depth of ditch required up to limit of the cranked portion to the axles.

85 Mounted upon the forward pointed end of the body 11 is a plow 28 having wings extending rearward on each side of the point of the body, and connected to this plow and extending upward therefrom are the mold boards 29 which are deflected so as to carry 90 the earth upward and laterally as it is cut out by the plow. Also mounted upon the forward end of the body is a yoke 30 which is pivoted at its rear end, as at 31, the forward end of this yoke being laterally 95 extended, as at 32, and supporting the rotatable cutting disks 33. These disks are disposed in a downwardly convergent relation on each side of the plow just forward of the mold board. The yoke passes 100 between connected vertical members 34 which are formed with transverse apertures so that a pin may be inserted to hold the cutters in any adjusted position.

105 Mounted upon the rear end of the body are the two scrapers 35. The scrapers extend upward and rearward, as illustrated.

The forward ends of these scrapers have tongues 36 which are inserted in slots 37 formed in the sides 12 of the body and are also supported by brackets 38 adjustably bolted to the upper web of the sheet metal which forms the body of the scraper, these brackets at their outer ends being bolted each to its corresponding scraper. These scrapers may be set to form a wide brim 10 to the ditch or a narrow brim therefor, as desired, and as the fashion requires.

The rear scrapers 35 are to be adjusted up or down or out or in so as to make the brim of the ditch wide or high. A wide 15 spread of the scrapers makes a shallow brim, while a narrow spread makes a relatively deep or high brim if the scrapers are raised up. It is not necessary to have the scrapers on while trimming old ditch banks. The 20 mold boards 29 are to elevate the dirt to each side of the ditch and the back scrapers are to be set to gather the loose dirt that the mold board does not get and place this dirt on the brim to form the bank. It is 25 not necessary to use the cutters in loose or soft ground, as these are only to be used in trimming ditch banks or cutting in hard ground. When not in use they are to be taken off. This machine is particularly adapted 30 for cutting irrigation laterals in grain fields and in loose ground. It can be used for other kinds of work as well, if so desired.

While the machine is particularly adapted 35 for cutting new irrigation ditches and cleaning out and re-cutting old irrigation ditches, it is obvious that it may be used for forming shallow trenches and a large variety of other work. By operating the 40 handles, the body of the machine may be raised off the ground or may be depressed below the level of the ground. Preferably the machine will have a seat for the driver so disposed that he may conveniently operate the levers controlling the depth of cut.

45 While I have illustrated details of construction it will be obvious that I do not wish to be limited thereto, as these may be varied in many ways without departing from the spirit of the invention.

50 I claim:—

1. A ditching machine of the character described comprising a sharp-pointed, approximately triangular body, a pair of transversely extending axles mounted upon 55 the body and having cranked ends, supporting wheels carried upon the cranked ends of the axles, manually operable means for oscillating the axles to raise or lower the body, a plow point mounted upon the forward end of the body and having upwardly extending mold boards on each side of the body, and cutting disks carried upon the forward end of the body above the rear end 60 of the plow point and forward of the mold boards.

2. A ditching machine of the character described comprising a sharp-pointed, approximately triangular body, a pair of transversely extending axles mounted upon the body and having cranked ends, supporting 70 wheels carried upon the cranked ends of the axles, manually operable means for oscillating the axles to raise or lower the body, a plow point mounted upon the forward end of the body and having upwardly extending mold boards on each side of the body, a yoke swingingly mounted upon the body adjacent its forward end and having laterally projecting members, rotatable cutting disks mounted upon said members and 80 disposed above and in front of the mold boards, and means for vertically adjusting the yoke to raise or lower the cutting disks.

3. A ditching machine of the character described comprising an approximately triangular, pointed body formed of sheet metal having downwardly extending sides, braces extending between said sides, a pair of transversely extending axles mounted in 90 bearings upon the upper face of the body and cranked at their ends, supporting wheels carried upon the cranked ends of the axles, manually operable means for oscillating the axles to depress or raise the body, a plow mounted upon the forward end of the body 95 and having mold boards extending upward on each side of the body, cutting disks adjustably mounted upon the forward end of the body and disposed above and in advance 100 of the mold boards, and scrapers adjustably mounted upon the rear end of the body and extending upward and laterally therefrom.

4. A ditching machine of the character described comprising an approximately triangular, pointed body formed of sheet metal having downwardly extending sides, braces extending between said sides, a pair of transversely extending axles mounted in 105 bearings upon the upper face of the body and cranked at their ends, supporting wheels carried upon the cranked ends of the axles, a plow mounted upon the forward end of the body and having mold boards extending upward on each side of the body, scrapers adjustably mounted upon the rear end of the body and extending upward and laterally therefrom, and manually operable means for oscillating the axles comprising 110 a lever mounted upon each axle, an arcuate rack over which the lever moves, and a manually retractable locking bolt engaging the rack, the lever being mounted for movement from a position with the wheels projected below the body to a position with the wheels retracted above the bottom of the body.

In testimony whereof I hereunto affix my signature.

ALBERT W. FULLER.
